2 SHEETS—SHEET 2.

UNITED STATES PATENT OFFICE.

ALFREDO QUINONES, OF NEW ORLEANS, LOUISIANA.

ELECTRICAL EXERCISING DEVICE.

1,253,885.

Specification of Letters Patent. Patented Jan. 15, 1918.

Application filed March 24, 1917. Serial No. 157,195.

To all whom it may concern:

Be it known that I, ALFREDO QUINONES, a citizen of the Republic of Salvador, and resident of New Orleans, in the parish of Orleans and State of Louisiana, have invented certain new and useful Improvements in Electrical Exercising Devices, of which the following is a specification.

This invention relates to exercising apparatus and has more especial reference to an improved electrical exercising device.

The invention has for its dominant object to provide a weight exercising device, which, when operated, will charge the body of the user with electric current, thus, providing means in addition to the pulling of the weight for stimulating and developing the muscles.

Another and equally important object of the invention is to provide the weight with novel electricity-generating means, whereby the same when operated, will produce the electricity for charging the body of the user, the said generating means being arranged to allow operation thereof at times and to prevent operation thereof at other times.

Among other aims and objects of the invention may be recited, the provision of a device of the character mentioned with a view to compactness, and in which the number of parts are few, the construction simple, the cost of production small, and efficiency and operation high.

Other and further improvements and novel details in the construction and arrangement of parts will be appreciated from the description to follow, which for a clear understanding of the invention should be considered in connection with the accompanying drawings forming a part hereof and wherein the preferred embodiment of the invention is shown for the purpose of illustration.

In the drawings:

Figure 1 is a perspective of my exercising device in operation;

Fig. 2 is a side elevation thereof;

Fig. 3 is a transverse section thereof; and

Fig. 4 is a similar view showing the generator in inoperative position.

Similar characters of reference are employed in all of the above described views to indicate corresponding parts.

Referring now more specifically to the

several figures of the said drawings, there is provided an angle plate of bracket designated 1, which bracket has secured thereto through the medium of screw eyes or the like, the upper extremities of ropes 2, the lower extremities of which are connected to the flooring of the building in which the device is arranged by means of screw eyes 3. A plurality of spaced pulleys 4 are arranged upon the vertical portion of the angle bracket 1 for a purpose which will be subsequently obvious. To the wall of the building adjacent the rope 2 there is secured a second angle plate 5 having a plurality of openings therein, certain of which receive the ropes 2 therethrough.

The weight comprises a substantially rectangular receptacle indicated by the numeral 6 having a hinged cover 7 thereon, which cover may be held in its closed position by the usual hasp and staple connection. Vertically aligned openings are formed within the bottom and closure of the receptacle whereby the ropes 2 may pass through the same, while through the bottom thereof a rubber pull 8 is secured through the medium of a screw eye 9, the lower extremity of the said pull being connected to the flooring of the room as at 10. It is of course obvious that various devices may be substituted in lieu of the rubber pull, such as contractile coiled springs or the like. Other screw eyes 11 are engaged with the hinged closure 7 of the receptacle and have secured thereto the adjacent extremities of ropes 12 passing downwardly from the pulleys 4 about which they are arranged. Hand holds 13 formed of metal are connected to the free extremities of the ropes 12 and serve as means for facilitating engagement therewith whereby to cause raising and lowering of the receptacle 6 when pulled.

A support 14 is hingedly mounted within the receptacle 6 as at 15 and is pivotally engaged by a hook 16 extending through the closure 7 thereof, thus, affording means whereby the support may be readily raised or lowered. To secure the support in its raised position, a slidably stop 17 having a hooked extremity is passed through one side wall of the receptacle and is adapted to be moved outwardly beneath a portion of the said support. To the lower face of the support 14, a dynamo 18 is fixedly secured and has mounted upon the extremity of its arma-

ture shaft a pulley 19, while upon the upper and lower sides of the said pulley, other pulleys designated 20 are arranged and are carried by suitable brackets 21 secured in a suitable manner to one side wall of the receptacle.

An induction coil 22 is also arranged within the receptacle 6, preferably adjacent one end thereof whereby to allow the swinging 10 of the dynamo 18 to inoperative position. Suitable electric conductors are connected to the terminals of the dynamo 18 and to those of the coil 22. Other conductors 23 are engaged with the induction coil 22 and extend 15 along the pull ropes 12 into engagement with the metal hand holds 13.

In operation, when it is desired to employ the electricity generating means of my improved exercising device, the dynamo support 20 is swung into its uppermost position as shown in the Fig. 2 whereupon it is locked by means of the stop 17. In this position, the adjacent guide ropes 2 will be caused to assume a tortuous course thereabout through 25 the medium of pulleys 20 arranged upon the upper and lower sides thereof and as a consequence, upon upward or downward movement of the receptacle due to the pulling of the ropes 12 will cause rotation of the dynamo armature shaft and hence, will generate electricity which will be delivered into the induction coil 22 and from there in its transformed state discharged into the body 30 of the user whose hands are engaged with the hand holds 13. Should it be desired to operate the exercising device without the electricity generating means, the stop 17 is disengaged from the dynamo support 14 whereupon the said dynamo will swing to a 35 position shown in the Fig. 4, the pulley 19 disengaging the guide ropes 2 and permitting the same to pass idly over the pulleys 20. Obviously, when in normal position, the receptacle 6 rests upon the angle brackets 5 and when pulled upwardly will be moved 45 against the tension of the rubber pull 8, thereby, offering sufficient resistance to cause the stimulating and developing of the muscles of a user.

50 If desired, weights of a suitable nature may be arranged within or secured to the receptacle 6, such as conditions or preference may dictate.

Manifestly, the construction shown is capable of considerable modification and such modification as is within the scope of my

claims, I consider within the spirit of my invention.

I claim:

1. In an exercising device, the combination with a receptacle movable over fixed ways and having hand holds connected thereto, of electricity generating means in said receptacle, means on the generating means engageable with certain of said fixed ways, 65 and means connected to the generating means for transforming the electricity and conducting it to the hand holds.

2. In an exercising device, the combination with a receptacle movable over fixed 70 ways and having hand holds connected thereto, of electricity generating means movably mounted in said receptacle and engageable with certain of the fixed ways at times, means for maintaining the generating means 75 in engagement with the fixed ways, and means connected to the generating means for transforming the electricity and conducting it to the hand holds.

3. In an exercising device, the combination with a receptacle movable over a plurality of guide ropes and having pull ropes and hand holds connected thereto, of a support hingedly mounted in said receptacle, a dynamo secured to said support and having 85 a pulley mounted on the armature shaft thereof, said pulley being engageable at times with one of the guide ropes, and means connected to the dynamo for transforming the current and conducting the same to the 90 hand holds.

4. In an exercising device, the combination with a receptacle movable over a plurality of guide ropes and having pull ropes and hand holds connected thereto, of a support hingedly mounted in the receptacle, a dynamo secured to said support, means engaged with the support for raising the same, other means engageable with the support for maintaining the same in raised position, 100 a plurality of pulleys mounted in the receptacle and arranged in spaced superposed relation, the armature shaft of the dynamo extending between said pulleys and having a pulley mounted thereon, said pulleys being engageable with one of the guide ropes, and means connected to the dynamo for transforming the electricity and conducting the same to the hand holds.

In testimony whereof, I affix my signature 110 hereto.

ALFREDO QUINONES.
